Primary Examiner—Ian Simmons*Assistant Examiner*—Carissa Fitts(74) *Attorney, Agent, or Firm*—Sterne, Kessler, Goldstein & Fox P.L.L.C.(57) **CLAIM**

The ornamental design for a portable lamp, as shown and described.

DESCRIPTION

FIG. 1 is a perspective view of a portable lamp showing a new design;

FIG. 2 is a top view thereof;

FIG. 3 is a side view thereof, the opposite view being a mirror image thereof; and,

FIG. 4 is an exploded perspective view thereof.

The broken line showing is included for the purpose of illustrating only and forms no part of the claimed design.
